UNITED STATES PATENT OFFICE

KANE Y. KONNO, OF CHICAGO, ILLINOIS

CALCULATING DEVICE

Application filed June 12, 1928. Serial No. 284,749.

My invention relates to handy devices for calculating purposes, and more particularly to the ancient abacus, and it is my main object to improve the latter to the extent of serving with equal facility for the operations of multiplication and division as for those of addition and subtraction.

A further object of the invention is to augment the abacus with an apparatus of movable ribbons to receive data by inscription, thus furnishing renewal surfaces for a new problem once the old one has been solved.

A still further object of the invention is to provide means for offsetting the partial products in multiplication by making one of the ribbon units shiftable.

Another object of the invention is to simplify the actions of analyzing and selecting values in the abacus by imparting shading or color to groups of counters, common to such values.

A significant object of the invention is to provide the same with a simple, mechanically shifting decimal point indicator, in order to adapt the decimal point to a position most convenient for a given problem.

A final, and important object of the invention is to incorporate my improvement in a simple structure of light material, whereby the cost of the device may be maintained at a low figure.

With the above objects in view and any others that may suggest themselves in the specification and claims to follow, a better understanding of the invention may be gained by reference to the accompanying drawing, in which—

Figure 1 is a plan view of the calculating device; and

Figs. 2, 3, and 4, are respectively, sections on the lines 2—2, 3—3, and 4—4 of Fig. 1.

Referring specifically to the drawing, 5 denotes the frame, 6 the dividing bar and 7 the counters of a typical abacus calculator. While calculators of this type have been used since time immemorial and are more popular in the Oriental countries, it may be mentioned at this time that the counters are divided into two groups, one each side of the

dividing bar 6. Thus, the single group shown above the dividing bar is in a series of multiple progression by the constant "10", in both directions from a given decimal point 8, such as 5, 50, 500, etc., in one direction and .5, .05, etc., in the other direction, as shown. While this row of counters deals with the numeral 5 and its multiples, the counters on the lower side of the dividing bar 6 deal with the multiples of the number "1". Considering the position of the decimal point 8 in the drawing, a few notations have also been indicated to show the values of the lower counters, such as a vertical row of "1" value, the next row of "10" value, the next row of "100" value, and so on, with increasing values and conversely in the opposite direction from the decimal point with decreasing values.

Since the abacus calculator is operated with speed by those who are experienced in its use, I have found it of especial value to incorporate therein means whereby to accomplish multiplication and division. Those familiar with devices for simplifying these methods by mechanical means know that multiplication involves addition; and that division involves subtraction. Thus, if a means is provided in conjunction with an abacus calculator whereby to distinguish and record such steps the abacus may be used with great facility to bring forth the result.

In carrying out the above analysis, I provide as an attachment, a frame extension 9 laterally of the abacus calculator and adjoining the single series of counters. The extension forms a base for a paper roll 10 from which a ribbon of paper is extended longitudinally. Over the ribbon 10a is a lid 11, spring hinged at 12, such lid being perforated with a number of openings 13 registering with the rows of counters 7. The lid 11 has a small knob 14 for a finger hold to swing back the lid in case any difficulty is presented in the sliding of the ribbon 10a. The latter serves for the entry of a given number for an abacus problem, and the openings individually expose the digits of such number. When the problem has been finished or solved, the ribbon may be drawn from the right hand end, according to Figure 1, 100

and the used portion torn away, leaving a fresh length for the inscription of the desired number of the next problem. Next alongside the arrangement just described, is a similar one in which the ribbon may be denoted by the numeral 15 and the roll by the numeral 16. The base 17 for this arrangement, however, is not stationary as in the previous case, but is mounted to slide on the extension frame 9, and be guided by a rod 18 near the extremity of the extension frame. The base 17 has depending ears 17a slidably mounted on the rod 18, as indicated more clearly in Figure 2, this relation retaining the slidable frame in alignment with the abacus array. The slidable base 17 is equipped with a handle 19 for the actuation of the same, and its movement is intended to be in steps corresponding to the succession of digits involved. In order that these steps may be determined, I provide the extension frame 9 with a series of depressions 20 into any of which a barb 21 carried by the slidable base 17 may fall, as clearly shown in Figure 3. In order to facilitate the transfer of the barbs from one depression to the other, I make the approach to each depression from either side inclined, as indicated at 22, so that in the movement of the slidable frame the barb 21 may readily drop into a given depression and may be transferred therefrom without difficulty. The changing positions of the slidable base owing to the operation of the barb 21 as described will be permitted by the pivotal relation of the base to the stationary rod 18, so that no difficulty will be experienced in producing the shifting movements from one point to another.

When a problem of multiplication is to be solved, the ribbon 15 is inscribed with the multiplicand and the ribbon 10a with the multiplier. Starting with the right-hand end of each of these numbers the process is to multiply mentally the first or extreme right-hand digit of the multiplier by the first and succeeding digits of the multiplicand. Thus, the product of the first single multiplication would probably be a number of two digits such as 63, 49 or the like, and this number is recorded in the first two rows of the abacus proper, the decimal point being ignored for the moment. The product of the first multiplier digit by the second multiplicand digit would be a similar number of two digits which is recorded in the abacus by adding the first digit into the value of the second row of counters, and recording the second new digit directly in the third row. This process continues until all the digits of the multiplicand have been multiplied by the first digit of the multiplier, so that the abacus is now arranged in a series of condensed preliminary products.

The process must now be repeated by the use of the second digit of the multiplier as

against all the digits of the multiplicand; but a move must be made, this being to shift the multiplicand bodily by moving the slidable base 17 one point to the left. This move registers the first digit of the multiplicand with the second row of the abacus as a source or origin. The multiplication of the second multiplier digit with the digits of the multiplicand now ensues as before, but each step is of course read into the abacus, so that while the first row of the abacus remains set and unchanged, all the succeeding rows have secured new values. The process just outlined is repeated until the multiplier is exhausted, at which time the resulting condition of the abacus spells the product or result of the problem. It is thus seen that the only writing necessary for the problem of multiplication was that of inscribing the multiplier and multiplicand, the working of the problem consisting merely of the shifting of the multiplicand from time to time and the absorption of new values into the abacus record by addition. Thus, large numbers can be multiplied with facility after a small amount of practice, reducing the time of arithmetical multiplication. A simple problem of multiplication is illustrated below.

$$\begin{array}{r}
 5349 \text{ multiplicand} \\
 1027 \text{ multiplier} \\
 \hline
 37443 \\
 10698 \\
 0000 \\
 5349 \\
 \hline
 5493423
 \end{array}$$

95

The steps of the above method are (1) that one must "carry" figures while working out each preliminary product, in order to save excessive writing; (2) that effort and facilities are necessary to write the preliminary and final products; and that the preliminary products are arranged in stepped relation, being consecutively moved the space of one digit. In my process the "carrying" and writing are not utilized, the working-out of the first preliminary product being as follows:

First step	$ \begin{array}{r} 5349 \\ 2 \\ \hline 63 \end{array} $	7 First digit of multiplier
	$ \begin{array}{r} 2 \\ 1 \\ 3 \\ 5 \\ \hline 63 \end{array} $	Set in abacus
	$ \begin{array}{r} 37443 \\ 10698 \\ 0000 \\ 5349 \\ \hline 5493423 \end{array} $	Not noted
Second step	$ \begin{array}{r} 5349 \\ 2 \\ \hline 18 \end{array} $	Second digit of multiplier
Multiplicand shifted once	$ \begin{array}{r} 5349 \\ 1 \\ \hline 8 \end{array} $	Added into abacus
	$ \begin{array}{r} 10698 \\ 1 \\ \hline 0 \end{array} $	Not noted
Third step	$ \begin{array}{r} 5349 \\ 1 \\ \hline 4 \end{array} $	Fourth digit of multiplier
Multiplicand shifted twice due to zero in the multiplier	$ \begin{array}{r} 5349 \\ 1 \\ \hline 3 \end{array} $	Added into abacus
Final product	$ \begin{array}{r} 5493423 \end{array} $	Aggregate reading in abacus

For division, the ribbon 15 is inscribed

with the divisor and the ribbon 10a left blank for the inscription of units in the quotient from time to time. The dividend is set in the abacus. By reversing the operation in the 5 case of multiplication, and shifting the slide-able base 17 from step to step toward the right, the units of the quotient may be de-veloped. To illustrate, the following is an 10 arithmetical example of a division prob-lem:—

$$\begin{array}{r}
 6128 \\
 153 \overline{) 987,584} \\
 918 \\
 \hline
 195 \\
 153 \\
 \hline
 428 \\
 306 \\
 \hline
 1224 \\
 1224 \\
 \hline
 0
 \end{array}$$

20 The above problem is laid out on my calculator thus:—

Divisor	1 5 3	Inscribed well to the left on ribbon 15.
Trial quotient	6	Inscribed on ribbon 10a.
Dividend	9 3 7 5 8 4	Recorded in abacus.

30 The trial-quotient is now multiplied by the consecutive digits of the divisor, and the 35 product shifted and subtracted each time into the abacus, thus:—

$$\begin{array}{r}
 \text{First step} \quad 153 \\
 \quad \quad \quad 6 \\
 \quad \quad \quad \underline{987,584} \\
 \quad \quad \quad -18 \\
 \quad \quad \quad 1919,584 \\
 \quad \quad \quad -30 \\
 \quad \quad \quad 619,584 \\
 \quad \quad \quad -6 \\
 \quad \quad \quad 19,584
 \end{array}$$

Reading on abacus at end of first step.

40 The divisor (153) is now shifted one point to the right, thus:

$$\begin{array}{r}
 \text{Divisor} \quad 153 \\
 \text{Quotient} \quad 6 \\
 \text{Remainder of dividend} \quad \underline{19584}
 \end{array}$$

45 The divisor is then "tried" into the dividend remainder, thus:

$$\begin{array}{r}
 153 \\
 61 \\
 \hline
 19584
 \end{array}$$

50 and the process repeated as before.

For ordinary or simple use, a much shorter embodiment of the calculator than shown would be sufficient. However, where one accustomed to the use of the abacus desires it for mathematical or laboratory use, it is well to provide it with the long series of units shown. Thus, in the case of multiplication, the multiplicand—inscribed on the ribbon 15—may be a considerably long number, 55 while the multiplier would most naturally be a short number, this example being made simply to indicate that the ribbon 15 should be of a considerable working length. Con-versely, in the case of division, it is often 60 necessary to secure a quotient to an infinite

extent, such as the familiar "pi—3.14159" which is a good reason for giving the working section of the ribbon 10a a considerable length.

For the purpose of the decimal point, 70 and the commas 23 ordinarily used to sepa-rate the hundreds in long numbers, I find it of benefit to equip the dividing bar 6 with a slide 24. This slide is preferably dovetailed into the dividing bar as in-dicated in Figures 2 and 4, and its ends are received in the end pieces of the frame 5, these being perforated as indicated at 5a for this purpose and also to permit the passage of the end portions of the slide when the lat-ter is shifted. The slide thus has a long shift-ing range and the decimal point may, there-fore, be positioned at any point between two rows of counters that may suit a particular problem involving decimal points. Thus, in 80 the case of a multiplication problem, the deci-mal points in the multiplier and multiplicand may be ignored during the working of the problem as in the case of arithmetical mul-tiplication; however, when the problem is 85 finished the decimal may be shifted a num-ber of steps representing the sum of the deci-mals in the multiplier and multiplicand, again as is done in arithmetical multiplica-tion, in order to ascertain the number of deci-mals in the product. In the case of division, 90 the decimal indicator is used in accordance with the established rules relating to deci-mals. For facility in operation, I provide 95 the slide 24 with a small finger knob or screw 100 24a coincident with the decimal point.

It is thus seen that I have provided a com-105 pact apparatus whereby the terms of prob-blems in multiplication and division may be set and the problems solved rapidly by those familiar with the use of the time honored abacus, saving the need of writing many numbers, and holding numbers over as in the case of ordinary multiplication or division. For facility in operating the abacus, the same 110 may be shaded or colored in groups as indi-cated so that one may more easily find a selected value which is common to a certain group, avoiding the selection of the value in a row which may not belong to the proper 115 group. Also, it will be noted that the lower series in the improved abacus have been re-duced from the customary five to four for the reason that the equivalent can be pro-duced without the need of the bottom series. 120 For example, 4 plus 1 will be represented by the upper counter 5, without the need of mov-ing a fifth counter to the first four lower counters in order to make five; or, in the case 125 of 9 plus 1, instead of having the array of the shifted upper counter with the five shift-ed lower counters, the counters in my case, that is, the shifted upper one and the shifted four lower ones may be cleared, and the 130

mental addition materialized by shifting the 10 value in the next row.

In conclusion, it will be apparent that my addition to the abacus is both simple in construction and in operation, and does not increase the cost of the device unreasonably when the benefits of the improvement are considered.

I claim:—

10. 1. The combination with an abacus formed with laterally-spaced rows of counters; of an entry ribbon carried by the abacus, said ribbon sheet extending in a lateral direction, and means spacing the entry ribbon off into divisions registering with the rows.

2. The structure of claim 1, said entry ribbon being shiftable in a lateral course.

3. The structure of claim 1, said entry ribbon being shiftable in a lateral course, and 20 means to divide the shifting movement into steps spaced as the rows.

4. The structure of claim 1, and a further entry ribbon in parallelism to the first-mentioned one and longitudinally-shiftable relative thereto.

5. The combination with an abacus formed with laterally-spaced rows of counters; of entry ribbons carried by the abacus for the original numbers of abacus problems, said 30 entry ribbons extending in a lateral direction, means for spacing the entry ribbons off into divisions for the digits of said numbers, such divisions registering with said counter rows, supports for the maintenance of the ribbons 35 in substantially flat position, and supply rolls from which the ribbons may be drawn as required.

6. The structure of claim 5, said means comprising lids carried by the supports to 40 cover the ribbons and perforated to define said divisions.

7. The structure of claim 5, said means comprising lids carried by the supports to cover the ribbons and perforated to define 45 said divisions and spring-hinged connections of the lids with the supports to keep the lids in contact with the ribbons.

8. The combination with an abacus formed with laterally-spaced rows of 50 counters; of an entry sheet frame extended from the abacus and formed with a series of depressions parallel to the counter series and spaced as the counter rows, an entry sheet slide associated with said frame, and a spur carried by the slide and adapted to drop into 55 said depressions as the slide is moved.

9. The combination with an abacus formed with laterally-spaced rows of counters; of an 60 entry sheet frame extended from the abacus and formed with a lateral series of depressions spaced as the counter rows, a rod carried by the frame in parallelism with the depression series, an entry sheet slide associated with 65 said frame and pivoted on said rod, and a spur

carried by the slide and adapted to drop into said depressions as the slide is moved.

10. The structure of claim 5, one of said supports being slidable into steps spaced as 70 the counter rows.

In testimony whereof I affix my signature.
